(57) **CLAIM**

We claim, the ornamental design for a photoelectric conversion element, as shown and described.

DESCRIPTION

The photoelectric conversion element is used as a light receiving element for converting a light signal (photo signal) to an electrical signal.

FIG. 1 is a front side view of a photoelectric conversion element showing our new design;

FIG. 2 is a back side view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front perspective view thereof; and,

FIG. 8 is a back perspective view thereof.
